(57) **CLAIM**

The ornamental design for a combined control and display cover, as shown and described.

DESCRIPTION

FIG. 1 is a perspective view of a combined control and display cover showing our new design.

FIG. 2 is a front elevational view of the combined control and display cover.

FIG. 3 is a right side view of the combined control and display cover.

FIG. 4 is a left side view of the combined control and display cover.

FIG. 5 is a top plan view of the combined control and display cover; and,

FIG. 6 is a bottom plan view of the combined control and display cover.

The broken lines in the Figures depict portions of the combined control and display cover that form no part of the claimed design.
